[57] CLAIM

The ornamental design for a skillet-oven, substantially as shown and described.

DESCRIPTION

FIG. 1 is a top rear perspective view of a skillet-oven showing one side of our new design;

FIG. 2 is a front elevational view thereof;

FIG. 3 is a side elevational view thereof opposite the side shown in FIG. 1;

FIG. 4 is a top plan view thereof; and,

FIG. 5 is a bottom view thereof.

FIG. 1

FIG. 2

FIG. 3

FIG. 4
